MODULAR CONNECTOR HOUSING

Wilmer Lee Sheesley, Harrisburg, and Dean Roosevelt Hooper, Jr., Middletown, Pa., assignors to AMP Incorporated, Harrisburg, Pa.

Filed Feb. 6, 1976, Ser. No. 655,642

Term of patent 14 years

Int. Cl. D13—03

U.S. Cl. D26—1 A

FIG. 1 is a perspective view of a modular connector housing showing our new design.

FIG. 2 is a front elevational view thereof.

FIG. 3 is a top plan view thereof.

FIG. 4 is a side elevational view thereof.

FIG. 5 is a rear elevational view thereof.

FIG. 6 is a front elevational view of a modular connector housing showing a modified form of the design of FIG. 2.

FIG. 7 is a front elevational view of a modular connector housing showing another modified form of the design of FIG. 2.

The top, rear and sides of FIGS. 6 and 7 are the same as those disclosed for FIG. 1.

We claim:

The ornamental design for a modular connector housing, as shown and described.
